(57) **CLAIM**

The ornamental design for a lighting fixture, as shown and described.

DESCRIPTION

FIG. 1 is a front right perspective view from below of a lighting fixture according to the new design;
FIG. 2 is a rear left perspective view from above thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a top view thereof;
FIG. 8 is a bottom view thereof;
FIG. 9 is a front right perspective view from below thereof, but shown illuminated;
FIG. 10 is a rear left perspective view from above thereof;
FIG. 11 is a front elevational view thereof;
FIG. 12 is a right side elevational view thereof;
FIG. 13 is a left side elevational view thereof;
FIG. 14 is a rear elevational view thereof;
